[57] CLAIM

The ornamental design for an electronic file communication unit used to receive and transmit electronic information, as shown and described.

DESCRIPTION

FIG. 1 is a front perspective view of an electronic file communication unit used to receive and transmit electronic information showing our new design;

FIG. 2 is a front elevational view thereof on a slightly reduced scale;

FIG. 3 is a right side elevational view thereof;

FIG. 4 is a left side elevational view thereof;

FIG. 5 is a rear elevational view thereof; and,

FIG. 6 is a bottom plan view thereof.
